UNITED STATES PATENT OFFICE.

LUDWIG THALLMAYER, OF BERLIN-CHARLOTTENBURG, GERMANY, ASSIGNOR TO SIEMENS-SCHUCKERTWERKE GESELLSCHAFT MIT BESCHRANKTER HAFTUNG, OF SIEMENSSTADT, NEAR BERLIN, GERMANY, A CORPORATION OF GERMANY.

SAFETY ARRANGEMENT FOR CHARGING DEVICES OF HOIST CAGES.

Application filed May 17, 1921. Serial No. 470,460.

To all whom it may concern:

Be it known that I, LUDWIG THALLMAYER, citizen of the Austrian Empire, residing at Berlin-Charlottenburg, Germany, have invented certain new and useful Improvements in Safety Arrangements for Charging Devices of Hoist Cages, of which the following is a specification.

My invention refers to hoisting devices and more especially to the charging devices used in connection therewith.

With charging devices for hoist-cages which are electrically or pneumatically operated there is a danger that the starting of the driving arrangement in the direction of the charging motion takes place before the hoist-cage is in such a position as to safely receive the trucks.

According to the present invention this danger is eliminated by the charging device being blocked for the forward movement of the trucks.

In the drawings affixed to this specification and forming part thereof an arrangement embodying my invention is illustrated diagrammatically by way of example. Referring to the drawings 1 is the pushing gear for the trucks which are carried along by the band 2 running over two pulleys 3 and 4. The pulley 4 is placed on a common shaft with the gear wheel 5. The gear wheel 5 is rotated by means of a worm 6. The worm 6 is mounted on the shaft of the motor 7 which is supplied with current from the mains 8. For the return motion of the pushing gear 1 the motor receives cur-

rent whenever the line 8 is connected to the motor through the conductor 9 and the regulating apparatus 10. This is effected by moving the lever 11 of the regulating apparatus 10 over to the right. For the forward movement of the pushing device 1 the motor 7 receives current from the mains 8 through the regulating apparatus 10 and the conductor 18 connected thereto. This is the case whenever the conductor 18 is connected to the mains through the switch 12, and when lever 11 is moved over to the left. The switch 12 is operated by means of the hoist-cage indicated at 13, this cage being provided with a projection 14. During the upward movement this projection 14 strikes a roller-lever 16 which is connected to the switch 12 by means of the rods 17. Thereby the roller-lever 16 is carried along from position I into position II, shown in dotted lines.

I claim:

1. In a device of the kind described in combination a hoist cage, means for pushing a truck onto said cage and means for blocking said pushing means so long as said cage is not in its correct position relatively to said pushing means.

2. In a device of the kind described in combination a hoist cage, means for pushing a truck onto said cage and electric means for blocking said pushing means so long as said cage is not in its correct position relatively to said pushing means.

In testimony whereof I affix my signature.

LUDWIG THALLMAYER.
